UNITED STATES PATENT OFFICE.

FRANK H. CADOGAN, OF UTICA, NEW YORK.

ELECTRIC SWITCH.

1,059,028.

Specification of Letters Patent. Patented Apr. 15, 1913.

Application filed October 14, 1910. Serial No. 586,984.

To all whom it may concern:

Be it known that I, FRANK H. CADOGAN, citizen of the United States, residing at Utica, in the county of Oneida and State of New York, have invented certain new and useful Improvements in Electric Switches, of which the following is a specification, reference being had therein to the accompanying drawing.

10 My invention relates to an electric switch and I declare the following to be a full, clear, concise and exact description thereof, sufficient to enable any one skilled in the art to make and use the same reference being 15 had to the accompanying drawings in which like reference characters refer to like parts throughout the specification.

The object of the invention is to provide a simple efficient switch whereby the lights 20 of an electric display sign may be automatically turned on and off at any desired or given time of the day or night. The invention accomplishes this object by placing in circuit the mechanism of a clock adapted to 25 revolve every twenty-four hours, a brush which is made to contact with the ends of any one or all successively of a plurality of members that represent a given period of time. The brush contacts with said members 30 in a manner whereby the circuit is made, so long as it remains in contact and is broken immediately said brush passes, in its revolution, the end of said member or members. This and other objects will be 35 readily apparent from the drawings, in which—

Figure 1 is a fragmentary, partial view of the mechanism of a clock in circuit with a switch and an electric display sign; Figs. 40 2, 3, 4 and 5 are respectively, a front elevation, a side elevation, a rear and a perspective view of the switch; Fig. 6 is a plan view of a switch, showing certain modifications; Fig. 7 is a detail view of one of the members 45 of said switch; Fig. 8 is a fragmentary view partially in section, showing the mounting of certain gear wheels; Fig. 9 is a plan view, in fragment, of a modified construction; Fig. 10 is a sectional elevation of another 50 modified construction; Fig. 11 is a plan of the construction shown in Fig. 10, completed; and Fig. 12 is a detail of a ring employed.

Referring to the drawings more particularly, I have here shown the partial mechanism of any clock having a gear 1 mounted 55 upon the hour spindle 2 thereof. Said gear

1 is in mesh with gear 3 adapted to make one revolution every twenty-four hours. Gear 3 has suitably secured thereto an arm 4 carrying brush 5 adapted to contact with the ends 20 of any one or all successively of a plurality of tip ups 6, provided with bores or holes 7^a in enlarged or sector portion 8 thereof, whereby same may be pivotally mounted 65 upon rod 9 having bearings at either end in the sides 10 and 11 of casing 7. The rotation rearward of tip ups 6 is limited by interference rod 12 also having bearings in sides 10 and 11 of casing 7. 70

In order to hold any one or all of tip ups 6 in angular position with reference to base 13 of casing 7, or so that ends 20 will be raised above a plane in which brush 5 of arm 4 moves, the invention embodies yoke 75 14 pivotally mounted as at 15 and 16 in sides 10 and 11 of casing 7. Said yoke 14 is held normally in the position shown in Fig. 5 or with bar 24 thereof upon the upper surfaces of ends 20 of tip ups 6, by 80 coiled spring 21 mounted upon rod 22 and having its ends hooked over arm or handle 23 of yoke 14 and edge of side 10 of casing 7. Said rod 22 has bearings in sides 10 and 11 of casing 7 and forms pivotal supports 85 for yoke 14. Yoke 14 is provided with handle 23 whereby the operator may rotate yoke 14 so as to raise bar 24 thereof and permit the rotation of any one or all of tip ups 6 whereby ends 20 thereof may come 90 to rest on top of bar 24 of yoke 14, so that any one or all of ends 20 of tip ups 6 may be held above the plane in which brush 5 of arm 4 moves and thus permit the withdrawal from the circuit of that particular half hour 95 represented by that particular end 20 of tip up 6.

The ends 20 of tip ups 6 are beveled in order that when the plurality of said ends are assembled the whole will be disposed in 100 the arc of a circle. In the drawings shown, each end 20 of tip ups 6 represent a half hour of time and hence in order to provide or adapt brush 5 of arm 4 to remain in contact an equal space or period of time with 105 each end 20, the tip ups 6 having ends 20 with the greatest amount of curvature are proportionally lessened in thickness.

In Fig. 6 I have shown a modified form of electric switch embodying a plurality of 110 contact plugs 30 having handles 31 and held in casing 32 adapted to permit the rearward sliding of said plugs 30, so that any one or all thereof may be removed from the line of

contact with brush 5 of arm 4. Plugs 30 have lugs *b* adapted to engage cross arms *d-d* to limit the movement forward and rearward of said plugs 30.

5 To properly connect the switch for actual operation, I mount same in an insulating manner by insulation 60 upon frame 40 of any suitable clock mechanism. Said switch is so disposed that brush 5 of arm 4 will just 10 contact with ends 20 of tip ups 6, in its revolutionary movement, when said ends 20 are disposed in the plane of said brush 5. One wire 41 leading from battery 42, or any suitable electric generator, may be connected directly to the frame 43 of the clock mechanism, and the other wire 44 connected to the electric sign 46. Wire 41^a is connected with the sign 46 and with switch, which I shall term generally 45, to complete the circuit. If it is desired to have the sign 46 lighted during any period of time, say during the hours eight and nine o'clock of the evening, tip ups representing said hours eight and nine o'clock are left in their normal position, whereby contact with brush 5 of arm 4 may be made, and the remaining tip ups 6 are disposed with their ends 20 above bar 24 of yoke 14, so that same will 25 not contact with brush 5 of arm 4, when said brush passes in its revolution said ends. 30

At the hour of eight o'clock, brush 5 of arm 4 will move into contact with ends 20 of tip ups 6 representing said hour and will remain in contact during the hour of eight 35 o'clock whereupon it will move to the ends 20 of tip ups 6 representing nine o'clock, which ends will be adjacent those representing eight o'clock, and will remain in contact here during said hour of nine o'clock. After 40 the hour of nine o'clock is passed or at ten o'clock, brush 5 of arm 4 will move out of contact with the ends 20 of tip ups representing eight and nine o'clock and the electric circuit will be broken, whereupon 45 the display sign 46 will have its lights turned off for the remainder of the night or until the brush 5 again comes in contact with said ends after the lapse of twenty-four hours.

50 In the event that it may be found desirable to connect wire 41 so that the current will not pass through frame 43 of the clock, gear wheel 3 may be insulated from the rest of the frame of the clock by insulation as at 55 50. It will also be necessary in this instance to insulate gear 1 as at 51. Further, there is mounted upon gear wheel 3 a metallic disk 52 in a manner so that said disk 52 will be held above said wheel 3 by collar 60 53 secured to wheel 3 and to disk 52 in any suitable manner. An arm 54 insulated by 65 from the frame 43 of the clock to which it is indirectly secured has an elbow 56

adapted to contact with the upper surface of disk 52 and is connected with wire 41 65 from the battery 42.

In Figs. 10 and 11 I have shown a still further modification embodying the idea of having the switch turn on or off the electric current at any period of the twenty-four 70 hours of the day. Tip ups 70 are mounted in a pivotal manner by rod 71 upon base 72 mounted upon frame 43 of the clock by insulation blocks 73. A wire hoop 74 is employed to hold any one or all of tip ups 70 75 in angular position, as seen by dotted lines in Fig. 10, whereby brush 75 secured to elbow 76 of arm 77 mounted upon a gear wheel 78 similar to wheel 3 of the former construction, may not make contact with the 80 ends 79 of tip ups 70.

Obviously any clock mechanism may be employed in combination with the electric switch described, and any disposition of said switch on said clock frame may be made by 85 well known gear mounting. The clock mechanism here shown is an eight day pendulum movement. The device may also be employed in any instance where any given make and break period in an electric circuit 90 is desirable.

Having thus described my invention what I claim as new and desire to secure by Letters Patent is:

1. In a device of the character described, 95 the combination of an arm having a brush, clock mechanism for moving said arm circumferentially, a casing pivotally holding a plurality of tip ups, a yoke pivotally mounted to said casing, spring means for holding 100 said yoke normally upon the upper surfaces of the ends of said tip ups, whereby said ends may lie in a plane to contact with said brush, and said ends of said tip ups adapted to be swung upon the upper side of said 105 yoke, whereby to avoid contact with said brush, substantially as described.

2. In a device of the character described, 110 the combination with an electric sign, a source of electric energy, a clock-mechanism and a series of tip-ups with ends adapted to complete a circuit including the sign, the 115 said electric-energy source and the clock, the said tip-ups being parallel with each other their ends forming a part of a circle and of a width whereby their contact-ends all present an equal surface for the travel of the contacting mechanism.

In testimony whereof I have hereunto affixed my signature in the presence of two 120 witnesses.

FRANK H. CADOGAN.
